CIGARETTE HOLDER

James R. Johnston, Detroit, Mich.

Application April 15, 1950, Serial No. 156,061

9 Claims. (Cl. 131—182)

This invention relates to improvements in a cigarette holder of the type having an articulation between the mouthpiece and the cigarette holding socket. This application is a continuation in part of my copending application filed February 7, 1949, Ser. No. 75,019, now abandoned.

An important object of the present invention is to provide an improved economically manufactured cigarette holder of simplified construction and operation having an articulated body to permit adjustment of the socket and cigarette held thereby to any convenient angle with respect to the mouthpiece.

A lighted cigarette will continue to draw or "breathe" for a few seconds after each draft by the smoker, so that even intermittent puffing at a cigarette will result in its substantially continuous drawing and the emission of smoke from its unlighted end within the smoker's mouth. This result is objectionable to many if not most smokers, since the enjoyment of a cool smoke is not possible unless the cigarette and smoker's mouth are permitted to cool in some way between drafts.

In the ordinary use of a cigarette holder, the aforementioned breathing between drafts is accentuated by the chimney effect of the holder. In order to realize the enjoyment of a cool smoke, it is necessary for the smoker to cool his mouth at intermittent periods either by parting his lips around the stem of the holder or by removing the latter from his mouth. In either instance smoke pouring from the unlighted end of the cigarette will fill the smoke conduit of the holder and will cause a gradual accumulation of an objectionable tarry residue. Furthermore, the chimney effect of the holder will cause the cigarette to burn appreciably faster than otherwise, resulting in considerable waste since the average smoker will have the holder in his mouth approximately only half of the time the cigarette is burning.

It is accordingly another object of the present invention to provide an improved cigarette holder having smoke release means whereby the chimney effect of the holder may be readily broken and the smoke readily blown from the smoke conduit to cool the same between drafts on the cigarette, and whereby breathing of the cigarette may be permitted without causing smoke to pour through the stem or mouthpiece of the holder. Thus the ordinary fouling of the smoke conduit by smoke condensate will be minimized and a cooler smoke will be achieved by maintaining a cooler smoke conduit.

Another object is to provide a cigarette holder having an improved articulation or joint between the mouthpiece and cigarette holding socket whereby the cigarette may be tilted to any desired angle relative to the smoker, the joint being ordinarily closed around the smoke conduit during smoking but being adapted to be selectively opened by the smoker to permit the escape of hot smoke between drafts and breathing of the cigarette without pouring smoke into the smoke conduit.

Another and more specific object is to provide an improved cigarette holder comprising a tubular socket mem-

2

ber and a tubular mouthpiece connected by a smoke conduit, the mouthpiece being detachably connected to a rearward end of the conduit and the socket member having a cigarette holding forward portion adapted to be detachably inserted through the bore of the smoke conduit from said rearward end so as to project from the forward end, the socket member also having a ball-like rearward portion adapted to seat against an annular inner retaining flange of the smoke conduit at the latter's forward end, thereby preventing forward passage of the ball-like portion completely through the smoke conduit and cooperating with said retaining flange to effect an adjustable articulation between the socket member and conduit. By virtue of this construction, the holder may be readily disassembled for cleaning. Preferably, the ball-like portion is spring pressed against its retaining flange to complete a substantially air-tight seal therewith at all angular adjustments of the smoking position.

In one embodiment of the present invention, a tubular ejector is provided having an enlarged head within the cigarette holding portion of the socket member and a tubular shaft extending through the bore of the socket member and projecting rearward therefrom. The ejector shaft is slidable forward relative to the bore of the socket member so as to eject a cigarette therefrom, but is suitably restrained against rearward movement by the structure of the holder. By this construction, the socket member may be moved rearward within the bore of the smoke conduit relative to the latter and to the ejector shaft so as to cause the enlarged head of the latter to press forward and eject a cigarette butt from the cigarette holding socket.

Another object is to provide a cigarette holder of the foregoing nature wherein the forward portion of the bore of the mouthpiece is dimensioned to receive a nicotine filter of standard size and a second tubular holder for a nicotine filter is located in the smoke conduit, the second holder having a socket or bore opening rearwardly coaxially into the forward opening of the mouthpiece bore, so that a nicotine filter seated within the socket of the second named filter holder will project rearwardly into the mouthpiece bore. By this construction the cigarette holder is readily adapted to be used selectively with nicotine filters of two different standard diameters. In a preferred construction, the second filter holder is provided with a forward projecting tubular stem adapted to abut the rearward end of the ejector stem during ejection. The forward portions of the second filter holder serve as a spring seat for a coil spring under compression around said stems and pressing forward against the ball-like portion to hold the same seated snugly against the retaining flange.

Other objects of this invention will appear in the following description and appended claims, reference being had to the accompanying drawings forming a part of this specification wherein like reference characters designate corresponding parts in the several views.

Although the present invention is particularly adapted for use by cigarette smokers and is illustrated herein by way of example in application with a conventional cigarette, it is to be understood that the holder is not limited to such an application and is readily adaptable for use with cigars or similar items. Accordingly the term cigarette as employed herein is to be interpreted to include all such tobacco or other smoking means, by whatever name customarily described, which may be suitably smoked while supported by a holder held within the smoker's mouth.

Details of two modifications of the present invention are illustrated by way of example in the drawings wherein: Fig. 1 is a longitudinal mid-section through a cigarette

holder embodying the present invention, showing in phantom the cigarette holding socket at an angular position of adjustment with respect to the mouthpiece.

Fig. 2 is a fragmentary view similar to Fig. 1, showing the cigarette holding socket in the ejecting position.

Fig. 3 is a transverse section taken in the direction of the arrows substantially along the line 3—3 of Fig. 1.

Fig. 4 is a view similar to Fig. 1, showing a modification of the present invention.

Fig. 5 is a section similar to Fig. 4, showing the cigarette holding socket in an angular position of adjustment.

Fig. 6 is a section taken in the direction of the arrows substantially along the line 6—6 of Fig. 4.

It is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Referring particularly to Figs. 1 through 3, an articulated cigarette holder is shown comprising a tubular socket member A and a tubular mouthpiece member B operatively connected by a tubular conduit C. The member A comprises a lightweight body 10 of any suitable material, such as an aluminum or magnesium alloy or molded plastic for example, having an integral spherical ball-like element 12 spaced from its rearward end by a constricted neck 14. The other end of the body 10 is provided with a forward opening cigarette receiving socket 16 having a slightly chamfered mouth 18 and adapted in depth to receive a coaxial tubular ejector element 20 slideable therein. Extending coaxially rearward from the body 10 through the neck 14 and ball-like element 12 is a tubular stem or smoke conduit portion 22 of the ejector 20, terminating in an enlarged annular flange 24 within the forward portion of the conduit C. In order to permit rearward movement of the element 12 in an ejector action as discussed hereinafter, the bore thereof enlarges conically rearward at 26 to receive the flange 24. It is apparent from the foregoing that a continuous conduit or opening is provided through the member A from the mouth of the socket 16 through the ball element 12.

The ejector 20 is freely slideable longitudinally within the socket 16 and is dimensioned to abut the rear end of a cigarette 28 inserted into the socket 16. Upon forward movement of the ejector 20 relative to the member A toward the mouth 18, the cigarette 28 will be ejected.

The member B comprises a conventional mouthpiece element 30 of suitable material, such as hardwood or molded plastic for example, having an enlarged body portion 32 tapering slightly forward for detachable insertion tightly into the rearward opening of the tubular conduit C. The latter comprises a generally cylindrical conduit formed of a lightweight metallic alloy or plastic material dimensioned to receive within its bore the body 10 and ball element 12 of the member A. The forward end of the bore of the conduit C is partially constricted by an annular inturned ball retaining flange or seat 34 having an internal diameter slightly less than the diameter of the ball element 12, but large enough to permit passage of the body 10 therethrough, Fig. 2. Thus forward displacement of the ball element 12 from the conduit C is prevented, but the entire member A may be withdrawn rearward through the conduit C. Thus the holder assembly may be readily taken apart for cleaning merely by pulling the tapered end portion 32 of the mouthpiece from the conduit C. Thereafter the socket member A is removable from the conduit C by sliding rearwardly through the bore thereof. A brush or cleaning fluid may then be run through the several bores. The adjacent contacting portions of the ball element 12 and annular flange or seat 34 are suitably polished to provide a substantially fluid tight seal between these elements when seated firmly to-

gether, as for example by the spring pressure of a coil spring 36 under compression within the conduit C between the rearward portions of the ball 12 and forward extremity of the mouthpiece member B.

In the present instance, the forward portion of the mouthpiece bore is enlarged to receive a tubular extension 38 snugly therein. The latter extends coaxially forwardly from the mouthpiece B and abuts the flanged ejector end 24 to prevent rearward movement thereof. Thus in order to eject a cigarette from the socket portion 16, the smoker need merely slide the socket member A rearwardly along the ejector stem 22 against the pressure of the spring 36 to the position indicated in Fig. 2.

By reason of the ball and socket articulation between the members A and C, the position of the cigarette 28 with respect to the mouthpiece B may be readily adjusted to any convenient angle, so that smoke arising from the cigarette will be least annoying to the smoker or his companions, or so that the cigarette may be tilted out of the 20 smoker's direct line of vision to avoid obscuring his view while he is working, reading, driving an automobile, or engaged in various other occupations.

When desired, the smoker may break the seal between the ball 12 and seat 34 to permit the aforementioned breathing of the cigarette. This is accomplished, when the socket member A is adjusted angularly with respect to the conduit C, merely by forcing the ball 12 rearwardly into the conduit C slightly away from the seat 34 sufficiently to break the chimney effect of the holder, but without ejecting the cigarette. Smoke pouring rearwardly into the conduit from the bore of the ball element 12 during the cigarette's breathing interval will thus be discharged around the ball to the atmosphere. If the smoker desires, cooling of the mouthpiece B may be expedited by gently blowing therethrough while the seal at the seat 34 is broken, discharging smoke to the atmosphere from the conduit C and minimizing the objectionable collection or condensation of combustion products therein and within the communicating bores of the mouthpiece B and tube 38.

Figs. 4, 5 and 6 illustrate a modification of the present invention which is particularly adapted for use selectively with two standard forms of nicotine filters. The general arrangement and function of the cigarette holding member A, mouthpiece member B and conduit C are the same as above described, except that the mouthpiece B is detachably secured to the rearward end of the conduit C in coaxial alignment therewith by a screw threaded connection. In place of the tubular member 38, the forward portion of the mouthpiece bore is enlarged at 40 to receive a nicotine filter insert therein of standard size. The filter insert may be of conventional construction and is accordingly not shown or described herein.

Abutting the forward end of the mouthpiece B is a tubular cylindrical member 42 having an integral forward tubular neck or extension 44 which abuts the rearward ejector flange 24 substantially in the manner above described regarding the tubular member 38. The bore 60 at the rearward end of the member 42 is enlarged at 46 to receive therein the forward end of a second type of nicotine filter insert of smaller diameter than the bore portion 40. Such an insert is indicated at 47 in phantom and may thus extend rearwardly into the bore 49. Accordingly the present holder is readily adapted for use selectively with two widely used nicotine filters of different dimensions.

As indicated particularly in Figs. 5 and 6, the forward end of the conduit C is provided with an enlarged hexagonal exterior which will prevent the holder from rolling when placed on a flat table. Thus the holder may be placed on a flat table with the socket member A containing a lighted cigarette tilted upwardly without danger of rolling and burning the table top.

It is also to be noted that the spherical extent of the

ball element 12 in Figs. 4 and 5 extends rearwardly considerably less than in Figs. 1, 2 and 3. Accordingly upon pivoting the socket member A to the limit of pivotal movement, Fig. 5, the rearward portion of the ball element 12 will be pivoted forwardly of the seat or flange 34, breaking the seal and permitting the aforementioned breathing action without causing smoke to pour through the conduit C and mouthpiece B and without necessitating rearward movement of the ball element 12 into the chamber of the conduit C. This structure is particularly advantageous since by a flick of the finger, the socket member A may be tilted to break the chimney effect of the holder and thereby decrease the rate of burning during the intervals when the holder is merely held in the smoker's hand. In all other respects, the holder described in Figs. 4, 5 and 6 is constructed and employed in the manner above described and may be readily taken apart for cleaning merely by unscrewing the mouthpiece B from the conduit C and sliding the member A rearwardly through the conduit C.

In operation of the cigarette holders shown in either Figs. 1 or 5, particularly when the member A is adjusted angularly with respect to the conduit C, the respective tubular extension 38 or 44 serves as a smoke baffle. Accordingly, smoke leaving the ejector conduit 22 will circulate in the cylindrical space between the conduit C and the corresponding extension 38 or 44 before entering the bore of the latter. Appreciable cooling of the smoke is thus effected through the sidewalls of the conduit C, permitting a cooler smoke by virtue of the present construction than is otherwise ordinarily possible.

I claim:

1. In an articulated cigarette holder, a tubular conduit, a tubular mouthpiece having a forward end detachably secured to the rear end of said conduit, a tubular cigarette holding socket member dimensioned to be passed through said conduit into either end and out the other, and articulated means connecting the socket member and conduit comprising a portion at the rear end of said socket member interfitting within the forward end of said conduit, said portion being dimensioned to be passed rearwardly through said conduit and out the rear end thereof.

2. In an articulated cigarette holder, a tubular conduit, a tubular mouthpiece detachably connected to the rear end of said conduit, a tubular cigarette holding socket member dimensioned to be passed through said conduit into either end and out the other, and articulated means adjustably connecting the socket member to the front end of said conduit for universal angular adjustment of the socket member with respect to the conduit.

3. In an articulated cigarette holder, a tubular conduit having an annular ball retaining seat at the forward end partially constricting the interior thereof, a tubular body having a ball-like element within said conduit seated against said seat to complete a ball-and-socket type articulation therewith, said body also having a cigarette receiving socket member projecting forwardly from said conduit and being dimensioned to be passed rearwardly through said annular retaining seat and to be separated from the conduit by being passed through the rear end thereof, the tubular body having a bore extending from said socket member into the interior of the tubular conduit through said ball-like element, a tubular mouthpiece detachably connected to the rear end of said conduit in communication therewith, and spring means yieldingly urging the ball-like element into seated engagement with the retaining seat.

4. In an articulated cigarette holder, a tubular conduit having an annular ball retaining seat at the forward end partially constricting the interior thereof, a tubular body having a ball-like element within said conduit seated against said seat to complete a ball-and-socket type articulation therewith and also having

a cigarette receiving socket member projecting forwardly from said conduit and being adapted to be passed rearwardly through said annular retaining seat, the tubular body having a bore extending through said ball-like element from said socket member to said tubular conduit, a tubular mouthpiece detachably connected to the rearward end of said tubular conduit in communication therewith, spring means yieldingly urging the ball-like element into seated engagement with the retaining seat, a hollow ejector slideable within said socket portion, a tubular stem extending within the bore of the body, said stem having a forward end connected with the ejector and in communication with the interior thereof and having a rearward flared end adapted to limit forward movement thereof through the bore of the body, said ball-like element having a rearwardly opening socket adapted to receive the flared end of said stem upon rearward movement of the body relative to the conduit, and abutment means adjacent said flared end adapted to limit rearward movement of the stem upon the body.

5. In an articulated cigarette holder, a tubular conduit having an annular ball retaining seat at the forward end partially constricting the interior thereof, a tubular body having a ball-like element within said conduit seated against said seat to complete a ball-and-socket type articulation therewith and also having a cigarette receiving socket member projecting forwardly from said conduit, the tubular body having a bore extending through said ball-like element from said socket member to said conduit, a tubular mouthpiece detachably connected to the rearward end of said conduit in communication with the bore thereof, a hollow ejector slideable within said socket portion, a tubular stem extending within the bore of the body, said stem having a forward end connected with the ejector and in communication with the interior thereof and having a rearward flared end adapted to limit forward movement thereof through the bore of the body, said ball-like element having a rearwardly opening socket adapted to receive the flared end of said stem upon rearward movement of the body relative to the conduit, and abutment means adjacent said flared end adapted to limit rearward movement of the stem upon the body.

6. In a cigarette holder, a tubular conduit having a mouthpiece at one end and an annular retaining seat partially constricting a bore in said conduit at the other end, a tubular body extending through the constricted bore at said other end, said body having a ball element within said conduit seated against said annular retaining seat to close the forward end of said bore and also having a cigarette receiving socket portion projecting forwardly of the constricted bore, the ball element comprising a spherical segment pivotally adjustable on said annular seat for adjusting the angular position of the socket member with respect to the conduit, the spherical surface of the segment terminating rearwardly of said ball element so as to be adapted to be swung through the constricted opening and open the bore of the conduit to the atmosphere upon pivoting of the body to a predetermined position, the bore of the body extending from the base of the socket portion through said ball element.

7. In a cigarette holder, a tubular conduit having an annular ball retaining seat partially closing the forward portion of a bore therein, a tubular mouthpiece detachably connected to said conduit at the rearward end thereof, a tubular body extending through the forward portion of said bore, said body having a ball element at one end within the conduit adjustably seated against said seat to close the forward end of the bore of the conduit between the seat and ball element and being pivotable for adjusting the angular position of the body with respect to the conduit, the body also

having a cigarette receiving socket member forwardly of the forward end of the conduit and dimensioned to be passed rearwardly through the conduit, the spherical surface of the ball element being engageable with said seat terminating at its rear portion so as to swing forwardly past the seat and open the forward end of the bore of the conduit to the atmosphere upon swinging of the body to a predetermined position with respect to the conduit.

8. In an articulated cigarette holder, a tubular structure comprising a tubular conduit and a tubular mouthpiece detachably secured to the rear end of said conduit in fixed relation with respect thereto, a tubular socket member having a socket portion at its forward end dimensioned to receive a cigarette therein, said member extending slidably into the forward end of said tubular conduit and having a ball portion pivotable within said conduit, said tubular conduit having a bore having a constricted opening forwardly of said ball portion adapted to limit forward movement of the latter, said opening and the bore of said conduit being dimensioned for passage of said member rearwardly therethrough upon detachment of said mouthpiece from said conduit, an ejector slidably axially within the socket portion of said member and pivotable with respect to said tubular conduit, said ejector having a stem extending rearwardly through said ball portion and having blocking means engageable with said tubular structure to limit axial rearward shifting of said ejector with respect to said conduit.

9. In an articulated cigarette holder, a tubular conduit having a bore therethrough, a tubular mouthpiece detachably connected to the rearward end of said conduit and in communication with the bore thereof, said conduit having an annular ball retaining seat at the forward end partially constricting the bore thereof, a

5 tubular body extending through the constricted end of said bore, said body having a ball-like element within said conduit seated against said seat to complete a ball-and-socket type articulation therewith and also having a cigarette receiving socket projecting forwardly from said conduit, said body having a bore in communication with said cigarette receiving socket and also in communication with the bore of the conduit through said ball-like element, spring means yieldingly urging the ball-like element into seated engagement with the retaining seat, a hollow ejector slidable within said cigarette receiving socket comprising a tubular stem connected at its forward end to the ejector and extending rearwardly through the bore of the body, and an 15 enlargement on the stem engageable with the forward end portion of the mouthpiece to limit rearward movement of said stem upon rearward movement of the body relative to said tubular conduit, said enlargement being also engageable with said body to limit forward movement of said stem with respect to said holding member.
